H. C. HART.

MAIL BOX.

No. 18,939.

Patented Feb. 26, 1889.

UNITED STATES PATENT OFFICE.

HENRY C. HART, OF DETROIT, MICHIGAN.

DESIGN FOR A MAIL-BOX.

SPECIFICATION forming part of Design No. 18,939, dated February 26, 1889.

Application filed January 16, 1889. Serial No. 296,551. Term of patent 7 years.

To all whom it may concern:

Be it known that I, HENRY C. HART, of Detroit, in the county of Wayne and State of Michigan, have invented a new and useful 5 Design for a Mail-Box, of which the following is a specification.

The object of this design is to provide a novel mail-box; and the leading features thereof consist of a lid, a door ornamented 10 with scroll-work, and a panel below the door ornamented with the representation of the head of a satyr.

The design is illustrated by the accompanying drawing, in which the figure is a perspective view of a mail-box.

In the drawing, the letter A indicates the complete box, consisting of the door B, lid C above the door, the ornamental top D above the lid, the panel E below the door, and lower 20 end, F. The top D is ornamented with scroll-

work, and the door B is ornamented with a double scroll which meets at a point in the center. The panel E is ornamented with the representation of the head of a satyr. The lower end, F, is fluted and beveled from all 25 sides toward the center, where it is provided with a ball, G.

Having thus described my invention, what I claim is—

The design for a mail-box, consisting of a 30 lid, C, the door B, ornamented with scroll-work, and a panel, E, below the door, ornamented with the representation of the head of a satyr, substantially as shown and described.

HENRY C. HART.
